INVENTOR:

Frank L. White,
by James Bagger, Esq.,
Attorney.

UNITED STATES PATENT OFFICE.

FRANK. L. WHITE, OF MONROE, LOUISIANA, ASSIGNOR OF ONE-HALF TO
JOHN B. STONE, OF SAME PLACE.

COTTON-PRESS.

SPECIFICATION forming part of Letters Patent No. 439,617, dated October 28, 1890.

Application filed May 16, 1890. Serial No. 352,067. (No model.)

To all whom it may concern:

Be it known that I, FRANK. L. WHITE, a citizen of the United States, and a resident of Monroe, in the parish of Ouachita and State of Louisiana, have invented certain new and useful Improvements in Cotton-Presses; and I do hereby declare that the following is a full, clear, and exact description of the invention, which will enable others skilled in the art to 10 which it appertains to make and use the same, reference being had to the accompanying drawings, which form a part of this specification.

This invention relates to certain new and useful improvements in apparatuses for compressing cotton and other materials, and more particularly in certain improvements upon the device described in an application for Letters Patent filed by me under date of January 15, 1890, Serial No. 336,980, allowed March 27, 20 1890.

These improvements consist, principally, in dispensing with the complicated gear mechanism embraced in said application for Letters Patent and substituting therefor the improved lever-lifting device, and also in providing suitable bracing devices, as will appear more fully hereinafter.

In the accompanying drawings, Figure 1 is a vertical sectional view of the complete device. Fig. 2 is a cross-sectional view on the line $\alpha\alpha$, Fig. 1; and Fig. 3 is a plan view of a portion of the movable platen.

Like letters of reference refer to like parts in all the figures.

Referring to the drawings, the working parts are shown as carried by a supporting-frame consisting of a base A, to which are secured four uprights B, said uprights being supported by longitudinal braces C C. These uprights are also united at their upper ends by means of a cross-head D, which forms the stationary platen of the press. The inner angles or corners of the uprights are faced by metallic strips E, which serve as tracks for a movable platen F, thus preventing the wear which would otherwise ensue to the uprights, and at the same time affording a smooth surface for the reciprocation of the platen. The upper portion of this platen, it will be observed, has extended reduced ends f, provided with angular notches f', which contact with the tracks before mentioned and form the upper bearing-surface of the platen.

Depending from the underside of the platen is an arm f², which terminates at its extreme lower end in four auxiliary arms f³, between which are journaled the ends of an anti-frictional roller G. This depending-arm has also secured to opposite sides thereof arms H H, said arms having their ends bent into angular 6c form and adapted to engage the tracks of the uprights, thus, in connection with the upper extended ends of the platen, forming a firm and steady support for the latter in its vertical line of movement.

The base A has secured near opposite ends cleats II, to which in turn are secured brackets J J', the latter being approximately U shape, so as to provide for the convenient insertion of the short inner lever L. This lever is pivoted in a bracket J, secured to the machine frame or base at one end thereof, and is provided upon its upper edge with a metallic strip N, which when said lever is in its proper position between the uprights of the frame, as clearly shown in the drawings, is adapted to bear against the anti-frictional roller journaled in the lower end of the depending arm of the movable platen. Beneath this lever is also arranged a metallic strip O, 80 extending the length of the lever and having its ends bent upwardly and formed into eyes o o'. This strip, as will also be seen, is bent downwardly at or near its center, and between this bent portion and the under edge 85 of the lever is inserted a wedge brace or block P, which is adapted to brace the short lever L at the point where the greatest strain occurs. The eye o is adapted to pass into the bracket J and registers with apertures (not 90 shown) in the sides thereof, a transverse bolt Q passing through said registering apertures and serving as the fulcrum of the lever. To the eye o' of the lever are pivoted by means of a transverse bolt R links S, the opposite 95 ends of said links being pivoted to a lug or arm m of the upwardly-extending long lever M. This latter lever is also provided at its lower end with a transverse aperture m', which registers with similar apertures j' j' in the 100 bracket J', said registering apertures receiving a transverse bolt T, which acts as the fulcrum for the lever.

Another important improvement which I have devised upon the apparatus described 105 in my application for Letters Patent before

mentioned is the employment of braces extending over the top of the press. These braces in the drawings are indicated by the letters U U and pass over the upper curved 5 surface of the stationary platen, fitting in suitable grooves formed therein, and their lower straight ends are provided with eyes u u, which receive the transverse bolts Q and T.

From the foregoing description the construction and operation of my improved apparatus, it is thought, will be readily understood. It will be seen that it is much more simple than the device described by me in application for Letters Patent filed January 15, 1890, Serial No. 336,980, and at the same time greater power is attained with less actual force being expended.

Having thus described my invention, what I claim, and desire to secure by Letters Patent 20 of the United States, is—

1. In a cotton-press, the combination, with a base-piece provided with uprights, said uprights having their inner angles or corners provided with metallic facings or tracks, of a 25 stationary platen connecting the upper ends of said uprights, a lower vertically-moving platen or follower working between the uprights, provided with extended ends having angular notches therein which fit the tracks 30 of the uprights, and also provided with a depending central arm, arms secured to the opposite sides of the latter arm and provided with bent ends fitting the tracks of the uprights, an inner short lever fulcrumed at its 35 forward end, arms secured to said central arm and embracing the said lever, a long lever suitably fulcrumed to the frame of the machine and provided at its forward end with an extending lug or arm, and links connecting the short lever with said extending lug or arm, substantially as set forth.

2. In a cotton-press, the combination with a base-piece provided with uprights, of a stationary platen connecting the upper ends 45 of said uprights, a lower vertically-moving platen working between the uprights and provided with a depending central arm, said arm terminating in a series of auxiliary arms, an anti-frictional roller journaled between 50 the same, a lever engaging with said anti-frictional roller, and means for operating said lever, substantially as set forth.

3. In a cotton-press, the combination, with a base-piece provided with uprights, of a stationary platen connecting the upper ends of 55 said uprights, a lower vertically-moving platen or follower working between the uprights and provided with a depending central arm, an inner short lever provided upon its upper 60 edge with a central metallic facing, arms secured to said central arm, embracing the said short lever, a metallic strip arranged beneath the lower edge of the lever and terminating at opposite ends in eyes, brackets secured to the base-piece and provided with transverse apertures, a transverse bolt passing through the registering eye and apertures in one of said brackets, a long lever provided with an arm or lug mounted in the other bracket and provided with an 65 aperture, a transverse bolt passing through said aperture and through the apertures of the bracket, links connecting an eye of the longitudinal strip with the arm of the long lever, and U-shaped braces passing over the upper curved surface of the stationary platen, the straight ends of said braces provided with eyes through which the transverse bolts pass, substantially as set forth.

ing through the registering eye and apertures of one of the brackets and forming the pivot of the short lever, a long lever provided with an arm or lug and having its other end fitting in the other bracket and provided with an aperture, a transverse bolt passing through said aperture and through the apertures of the rear bracket, and links pivotally connecting the rear eye of the longitudinal strip 75 with the upwardly-extending arm of the long lever, substantially as set forth.

4. In a cotton-press, the combination, with a base-piece provided with uprights, of a stationary platen connecting the upper ends of 80 said uprights, a lower vertically-moving platen or follower working between the uprights and provided with a depending central arm, an inner short lever provided upon its upper edge with a metallic facing, arms secured to 85 said depending arm, embracing said short lever, a metallic strip arranged beneath the lower edge of the lever and terminating at opposite ends in eyes and provided at or near its center with a bent portion, a wedge brace 90 or block inserted between said bent portion and the under edge of the lever, a transverse bolt passing through an eye in the metallic strip and forming the fulcrum of the lever, a long lever fulcrumed in the frame of the machine, and a link pivotally connected with the lower end of said long lever and with the metallic strip, substantially as described.

5. In a cotton-press, the combination, with a base-piece provided with uprights, of a stationary platen connecting the upper ends of said 100 uprights, a lower vertically-moving platen or follower working between the uprights and provided with a depending central arm, an inner short lever provided upon its upper edge 105 with a central metallic facing, arms secured to said central arm, embracing said lever, a metallic strip arranged beneath the lower edge of the lever and terminating at opposite ends in eyes, brackets secured to the base-piece and 110 provided with transverse apertures, a transverse bolt passing through the registering eye and apertures in one of said brackets, a long lever provided with an arm or lug mounted in the other bracket and provided with an 115 aperture, a transverse bolt passing through said aperture and through the apertures of the bracket, links connecting an eye of the longitudinal strip with the arm of the long lever, and U-shaped braces passing over the 120 upper curved surface of the stationary platen, the straight ends of said braces provided with eyes through which the transverse bolts pass, substantially as set forth.

In testimony that I claim the foregoing as 125 my own I have hereunto affixed my signature in presence of two witnesses.

FRANK. L. WHITE.
